UNITED STATES PATENT OFFICE.

HENRY H. WHITNEY, OF DEERING, MAINE.

DESIGN FOR A CHECK-HOOK.

SPECIFICATION forming part of Design No. 27,476, dated August 3, 1897.

Application filed April 16, 1897. Serial No. 632,514. Term of patent 14 years.

To all whom it may concern:

Be it known that I, HENRY H. WHITNEY, a citizen of the United States of America, residing at Deering, in the county of Cumberland and State of Maine, have invented and produced a new and original Design for Check-rein-Hooks; and I do hereby declare the following to be a full, clear, and exact description of the invention, such as will enable others skilled in the art to which it appertains to make and use the same.

Figure 1 is an elevation of my check-hook, showing my new design; and Fig. 2 is a top plan view of the same.

As shown in the drawings, the leading or material features of my design consist in a long oval base substantially semicircular in cross-section, the base-line curving slightly downwardly at the forward end and upwardly at the rear end, the configuration changing from semicircular to substantially oval cross-section at the forward termination of the base. The contour of the interior of the ring formed by the hook and closure-bar is substantially egg shape and bounded by continuous curved lines. At a point some distance from the rear end rises from the top of the base a curved closure-bar forming a mate-

rial portion of the egg-shaped ring of the complete hook, said closure-bar, whether seen from either side or from the rear, having the appearance of unbroken continuity with the base. The configuration of the closure-bar is that of the segment of two similar curves, one end of each being united and combined, the interior curve of the lower one forming a symmetrical continuation of the interior side of the hook proper and the interior curve of the upper one a symmetrical continuation of the external surface of said hook. As seen from the rear, the horizontal lines are continuous.

The design as herein set forth is for a hook all the visible parts of which are bounded by continuous curved lines.

I claim—

The design for a check-hook herein shown and described.

In testimony whereof I affix my signature, in presence of two witnesses, this 8th day of April, A. D. 1897.

HENRY H. WHITNEY.

Witnesses:

NATHAN CLIFFORD,
WALTER T. CAMP.
